UNITED STATES PATENT OFFICE.

WILLIAM FULLER HOSFORD, OF OAK PARK, AND DAVID LEVINGER, OF CHICAGO, ILLINOIS, ASSIGNORS TO WESTERN ELECTRIC COMPANY, INCORPORATED, OF NEW YORK, N. Y., A CORPORATION OF NEW YORK.

STRAND-WORKING MECHANISM.

Application filed December 17, 1924. Serial No. 756,405.

This invention relates to improvements in strand working mechanisms, and more particularly to wire drawing apparatus.

The object of the invention is to provide an improved wire drawing apparatus where in different types of wire storage mechanisms may be interchangeably mounted upon a common supporting portion thereof and operatively connected to a common driving means embodied in the apparatus.

In accordance with the general features of the invention a wire drawing mechanism is provided with a common supporting surface and a single operative connection for associating interchangeably in supporting and driving relationship therewith, either a wire coil take-up mechanism formed as a unit, attachable to the wire drawing mechanism and detachable therefrom, or a spool take-up mechanism also formed as a unit, attachable to the wire drawing mechanism and detachable therefrom.

One of the advantages of this construction is that a wire drawing mechanism embodying the invention will be more compact and occupy less floor space than a machine provided with both spool and coil take-up mechanisms permanently attached thereto. There is a further advantage that where a battery of wire drawing mechanisms of this type is employed it is not necessary to have both a spool and coil take-up for each machine, but a spool take-up may be provided for each of the machines and a lesser number of coil take-up mechanisms provided where the machines are used primarily for storing wire on spools; and on the other hand a coil take-up mechanism may be provided for each wire drawing apparatus and a lesser number of spool take-ups provided where the machines are used primarily for storing the drawn wire in the form of coils. A further advantage of the present invention resides in the fact that the driving mechanism for the wire drawing apparatus is provided with a single operative connection which may serve for either the spool or the coil take-up mechanism, rather than to provide the driving mechanism with two operative connections, as is the practice in some instances when the machine is equipped permanently with both spool and coil take-up mechanisms.

It is believed that the invention will be clearly understood from the following de-

scription taken in connection with the accompanying drawings illustrating one embodiment of the invention, in which,

Fig. 1 is a front elevation of a wire drawing machine embodying the features of the invention;

Fig. 2 is a fragmentary plan view thereof;

Fig. 3 is a front elevation of a wire coiling mechanism adapted to be interchangeably mounted upon the machine with the spool take-up mechanism illustrated in Figs. 1 and 2;

Fig. 4 is a schematic plan view of the driving mechanism for the drawing elements and the interchangeable wire storage mechanisms, and

Fig. 5 is a schematic plan view of the driving mechanism for the wire coiling mechanism illustrated in Fig. 3.

Referring to the drawings, 10 is a bed or base plate upon which is mounted a housing 11 provided with an upper suitably hinged section or cover 12 which is adapted to be swung open by pulling upwardly handles 13 formed in the front face thereof. Mounted upon the base plate 10 to the rear of the housing 11 is a second housing 15 for the driving mechanism to be described in greater detail hereinafter. The base plate 10 is provided upon its upper surface at the right hand side thereof with a portion 16 adapted to have mounted thereon interchangeably either a spool take-up mechanism indicated at 17 in Figs. 1, 2 and 4 or a coil take-up mechanism indicated at 18 in Figs. 3 and 5.

Either of the mechanisms 17 and 18 may be secured to the portion 16 by a plurality of screws indicated at 19-19 which may be passed through either of the base plates 22 and 23 of the mechanisms 17 and 18, respectively, and threaded into openings provided in the portion 16. Suitably journaled within the housing 15 is a pair of horizontally disposed driving shafts 24 and 25 (Figs. 1, 2 and 4), the shaft 24 being rotated from a motor (not shown) positioned in a basement or pit below the machine. The motor is operatively connected to the shaft 24 by a sprocket chain drive indicated at 26 and the shaft 25 is driven at a suitable speed from the shaft 24 also by a similar drive indicated at 28. The shaft 24 extends through the rear wall of the housing 11 and has secured at its forward end by a key 29, as shown in

Figs. 1 and 4, a conical or stepped drawing drum or capstan 30 provided with eight steps and the shaft 25 also extends into the housing 11 and carries a plurality of sheaves 31—31, seven of which are stepped in gradually decreasing diameters beginning at the forward end of the shaft and are mounted loosely thereon. Fixed to the shaft 25 by a key 32 at the rear of the seventh sheave 31

5 10 is a drawing drum or capstan 33. Secured to the inside of the rear wall of the housing 11 intermediate the shafts 24 and 25 is a die box or support 34 adapted to hold eight wire drawing dies 37—37, the dies being positioned and retained therein with their axes suitably disposed with respect to the periphery of the stepped capstan 30 and the sheaves 31—31 and capstan 33. Carried outside upon the left hand vertical end wall of the housing 15 is a trough like member 38 carrying tallow or other suitable lubricating material within which is mounted a die 39 through which the wire is first drawn. A guiding sheave 40 is rotatably mounted between a pair of ears 41 formed integrally upon the left hand end of the member 38 and over which the rod or wire 42 to be drawn down to a smaller size is led from the supply source (not shown).

20 25 30 Suitable means (not shown) is provided for lubricating the dies 37—37 mounted in the die box 34 and at the right hand side of the capstan 30 is a lubricator header 45 provided with a plurality of nozzles 46—46

35 40 45 which direct the lubricant onto the periphery of the different steps of the capstan 30. Upon the outside of the right hand vertical end wall of the housing 15 is mounted a support or housing 47 adapted to suitably position another wire drawing die 48 which is the final or finishing die.

45 50 The dies 37, 38, and 48 are first accurately strung upon the wire or rod 42 so that upon stringing the wire drawing machine, each die will drop into its allotted position in the die holders. A mechanism adapted to string the dies upon the wire in this manner is fully disclosed in the copending application of F. Murphy, Serial No. 681,922, filed December 21, 1923.

55 60 65 In stringing the wire drawing machine the end of the wire to be drawn, with the dies properly strung thereon, is passed over the guide sheave 40, the die 39 is positioned in the member 38, the wire is then passed over the top of and wrapped one or more turns around the capstan 33, the first of the series of dies 47 is then properly positioned in the die box 34, the wire is then passed one or more turns around the smallest diameter capstan 30, then underneath and over the top of the smallest diameter sheave 31, then the second of the series of dies 37 is properly positioned in the die box 34 and the wire is then passed over and

70 around the second smallest diameter capstan 30 one or more turns. This procedure is continued until the last die 48 is reached, which is carried in the housing 47.

The mechanisms 17 and 18 are each 70 adapted to be driven from a common driving mechanism when mounted upon the portion 16 of the plate 10 in the following manner.

75 Suitably journaled in the housing 15 at the right hand end thereof is a horizontally disposed shaft 51 which extends through the front wall thereof with its forward end supported in a journal indicated at 52. The shaft 51 is driven from the shaft 24 by a 80 sprocket chain drive 53 and is operatively connected to a suitably journaled vertically disposed shaft indicated at 54 in Figs. 1, 3 and 4 through bevel gears 55 and 56, the lower end of the shaft 54 having fixed 85 thereto a bevel gear 59.

90 Detachably mounted upon the extreme forward end of the shaft 51 by a set screw 60 and a key 61 is an auxiliary drawing element or capstan 62 which draws the wire 95 through the final reducing die 48 and thereafter it is taken up by the spool take-up mechanism 17 shown in the drawings mounted upon the portion 16 of the base 10. When the coil take-up mechanism (Figs. 3 and 5) is being used the auxiliary capstan 62 is not necessary and may be easily removed from the shaft 51 and a suitable guarding cap (not shown) positioned over the projecting end of the shaft 51 to prevent possible injury to the operator. A 100 guard 63, suitably supported, is provided for the auxiliary capstan which is also removed when the capstan is detached from the shaft 51.

105 110 115 As illustrated in Figs. 1, 2 and 4 the spool take-up mechanism 17 comprises a horizontally disposed shaft 66 suitably journaled upon the base plate 22 and adapted at its forward end to support a removable take-up spool 67. The shaft 66 is operatively connected to the shaft 54 through a horizontally disposed shaft 68 having fixed thereon at opposite ends bevel gears 69 and 70 which respectively mesh with the bevel gear 59 carried by the shaft 54 and a bevel gear 71 secured upon the shaft 66 (Fig. 4). The shaft 68 forms a permanent part of the mechanism 17 and is suitably journaled upon the base plate 22 thereof. Surrounding the shaft 68 is a housing 74 enlarged at its left hand end as indicated at 75 to surround the bevel gear 69 and provided with a flange 76 which is secured by screws 73 around an opening (not shown) in the 120 right hand end wall of the housing 15. When the base plate 22 is properly secured to the portion 16 of the base plate 10, the bevel gear 69 is in mesh with the bevel gear 59 and the drive to the shaft 66 is then com- 125 130

plete. For distributing the drawn wire in even layers back and forth across the spool 67 the following mechanism, also embodied in the take-up mechanism 17 is provided.

5 To the rear end of the shaft 66 is secured a pinion 77 which meshes with an idler gear 78 in turn meshing with a gear 79 fixed to a horizontal shaft 80 positioned above the shaft 66. The pinion 77 and gears 78 and 79 have been shown in offset relation in the schematic illustration for the sake of clearness. As shown in Fig. 1 the shaft 80 is provided with right and left hand screw threads 83 and 84, respectively, which are 15 traversed alternately by a lug (not shown) carried by a block 85 reciprocably mounted upon a pair of rods 86. Suitably carried by the reciprocable block 85 is a pair of distributor fingers 87 between which the wire 20 being fed by the capstan 62 is led and as the block 85 travels backward and forward due to the threads 83 and 84 and associated mechanism the wire is distributed in alternate directions across the spool 67 and between the flanges thereof in smooth even layers. This type of distributing mechanism is old in the art of spooling and a more detailed description thereof it is believed is not necessary.

25 Due to the constant speed at which the wire is received by the spool 67 and the increasing diameter of the spooled wire upon the spool it is necessary to gradually decrease the speed of the spool to maintain a 30 uniform tension on the wire. This is accomplished in the embodiment illustrated, by splitting the shaft 66 intermediate the bevel gear 71 and the forward end thereof carrying the spool 67, and mounting therebetween a suitable slip clutch indicated at 88. The clutch 88 comprises two abutting friction disks 91 and 92, one mounted upon each section of the shaft 66, the disk 91 being slidably mounted upon the forward section of the shaft. The friction between the disks 40 may be regulated by turning a nut 93 screw threaded upon the forward section of the shaft 66 which acts upon a compression spring 94 mounted upon the shaft and between the nut 93 and disk 91 to either decrease or increase the tractive force of the disk 92 upon the disk 91.

When it is desired to take up the drawn wire in the form of coils the spool take-up mechanism 17 may be detached from the portion 16 of the base plate 10 by simply removing the screws 19 and 73 whereupon the mechanism 17 may be lifted from the portion 16 and the coil take-up mechanism 18 illustrated in Fig. 3 may be mounted in operative relation to the wire drawing machine by reinserting the screws 19 in the base plate 23, and the screws 73 in a flange 81 formed upon a housing 82, the flange 81 being similar to the flange 76 upon the hous-

ing 74 of the mechanism 17. As explained hereinbefore, the capstan 62 and guard 63 are preferably removed from the wire drawing machine when the mechanism 18 is in use.

70 Referring to Figs. 3 and 5 which illustrate the coil take-up mechanism 18, 95 is a rotatable block or head around which the drawn wire is adapted to be coiled. The head 95 is fixed to the upper end of a vertically disposed shaft 96 suitably journaled in a supporting standard 97 integral with the base plate 23. Fixed to the lower end of the shaft 96 is a gear 98 which is in mesh with a gear 99 secured to the upper end of a vertically disposed shaft 100 carrying at its lower end a bevel gear 103 in turn meshing with a bevel gear 104 fixed to one end of a horizontally disposed shaft 105 which corresponds to the shaft 68 of the spool take-up mechanism 17. Upon the opposite end of the shaft 105 is a bevel gear 106 which, when the mechanism 18 is in position upon the portion 16, meshes with the bevel gear 59 fixed to the shaft 54. The shafts 100 and 105 are suitably journaled upon the standard 97, which also supports at its upper end a stationary cylindrical shell or guard 107 positioned around the rotatable head 95. The guard 107 is provided with a slot 108 extending in a vertical direction from its upper edge through which the drawn wire passes as it is coiled around the head 95 during the operation of the mechanism.

100 Combined with the coil take-up mechanism 18 and mountable therewith as a unit upon the portion 16 is a coil stripping mechanism 111. The function of the mechanism 111 is to relieve the attendant of the physical strain of removing the coils of wire, which are quite heavy, from the head 95.

105 Removably mounted within a suitable opening formed axially in the shaft 96 is a rod 112 carrying at its upper end a head 113. Pivots connected to the underside of the head 113 as indicated at 114 are four legs 115 spaced 90° apart and provided at their lower ends with feet 116. The lower ends of the legs 115 when in operative position as shown in the drawings fit within four vertically disposed recesses 118 formed in the peripheral face of the head 95 in such a manner that the outer faces of the legs and feet are flush with the peripheral face of the head. Reciprocably mounted upon the rod 112 is a member 119 provided with four arms spaced 90° apart. Each leg 115 is connected with an arm of the member 119 by a link 120, the links being pivotally connected to the legs and arms.

110 120 125 130 When a length of rod or wire 42 has been drawn and completely taken up around the head 95 and the legs 115 of the mechanism 111, the mechanism may be lifted from op-

erative engagement with the head 95 by latching a hook 121 depending from the free end of an arm 122 into an eye 125 fixed to the upper end of the head 113. The arm 122 is pivotally secured to a ram 126 of suitable pneumatic lifting apparatus 127 which is controlled by operating a valve handle 128. The apparatus 127 is supported upon a table 129 fixed to the standard 97 at the rear thereof as viewed in Fig. 3, the table serving as a platform for depositing the coil of wire 130 upon its release from the mechanism 111.

The member 119 and links 120 are so arranged that in the position shown in the drawings the legs 115 are retained in the position shown due to the weight of the member 119 and the cooperative toggle action between the member 119 and links 120, while if the member 119 is moved upwardly upon the rod 112 the legs will turn upon their pivot points 114 in a counterclockwise direction, thereby causing the feet 116 to move toward the axis of the rod 115. This inward movement of the feet 116 can only take place when the mechanism 111 is removed from operative engagement with the mechanism 18, which is accomplished in the following manner. The hook 121 is first attached to the eye 125, the handle 128 is then operated to cause the ram 126 to move upwardly, thereby carrying the coil stripping mechanism 111 and the coil of wire with it, the rod 112 sliding out of the opening in the shaft 96. The arm 122 is then swung by hand to a position over the table 129 and the member 119 is moved upwardly upon the rod 115 which will cause the feet 116 to move inwardly as hereinbefore described whereupon the coil of wire 130 will drop onto the table 129. Upon the operator releasing the member 119 after the release of the coil 130 the parts will return to their normal position as shown, due to the action 45 of gravity.

In Fig. 4 a suitable friction clutch is indicated at 133 which is adapted to connect the sprocket chain drive 53 with the shaft 51 and consequently adapted to control the rotation of the shaft 51 and either of the mechanisms 17 and 18 depending upon which one is operatively connected to the wire drawing machine. The clutch is controlled by the movement of an operating lever 134 (Figs. 1 and 2) mounted upon a rod 135 which is suitably connected to a shifting fork 136.

The wire drawing machine as hereinbefore described, provided with a common supporting surface and a single operative connection for associating interchangeably in supporting and driving relationship therewith either a coil or a spool take-up mechanism provides an efficient arrangement for a mechanism of this type and one which conserves floor space.

What is claimed is:

In a wire drawing apparatus, a die, a capstan for drawing wire through the die, a driving means for the capstan, a gear operatively associated with the capstan driving means, a member secured to the wire drawing apparatus, a removable wire storing mechanism, a shaft having a gear for connecting the wire storing mechanism with the gear associated with the capstan driving means, and a rigid member surrounding the shaft and attachable to the member secured to the wire drawing apparatus to predeterminedly space the wire storing mechanism with respect to the gear associated with the capstan driving mechanism to insure a proper meshing of said gear with the gear carried by the shaft.

In witness whereof, we hereunto subscribe our names this 8th day of December A. D., 1924.

WILLIAM FULLER HOSFORD.
DAVID LEVINGER.
